FLUSHING ASSEMBLY FOR CENTRIFUGAL
SEPARATORS

George J. Strezynski, Red Oak Mills, N. Y., as-
signor to The De Laval Separator Company,
New York, N. Y., a corporation of New Jersey

Application December 30, 1947, Serial No. 794,668

14 Claims. (Cl. 233—46)

1

This invention relates to centrifuges and more particularly to a centrifugal separator having improved means for feeding a flushing liquid into the separating chamber of the centrifugal bowl, usually at the peripheral portion near outlets for separated solids, as for the purpose of facilitating the discharge of the solids or washing the solids, or both, during the separating operation.

Heretofore, the introduction of a flushing liquid into centrifugal bowls has involved rather serious difficulties, since the liquid must be conveyed from a stationary duct to a suitable part of the bowl which is rotating at high speed. Moreover, the liquid must be fed to the bowl without interfering with the feed of the mixture to be separated or the discharge of the separated constituents. In prior centrifuges, the devices for feeding the flushing liquid into the bowl have not been entirely satisfactory for various reasons, among which are the complexity of the construction, the tendency for the flush liquid to leak from the feeding device and reach the bearings or other parts of the machine which are adversely affected by the liquid, and the difficulty of removing the bowl from the frame without interference from the feeding device. For example, a feeding device commonly employed for the flushing liquid comprises a stationary feed pipe mounted on the frame with its discharge end located in an annular recess at the central part of the bowl from which the liquid is delivered centrifugally through outwardly extending flush tubes in the bowl to the separating chamber. The annular recess is open toward the bowl axis to receive the stationary feed pipe, and the bowl has an inwardly extending annular ledge forming the bottom of the recess, the discharge end of the feed pipe overlying the ledge so that the latter will catch the liquid dripping from the pipe. This construction is objectionable not only because the flushing liquid leaks or spatters through the space surrounded by the bowl ledge, but also because the part of the stationary feed pipe overlying the ledge prevents the bowl from being lifted from the frame without first displacing or removing the feed pipe.

One object of the present invention, therefore, resides in the provision of a centrifuge having improved means for feeding flushing liquid into the separating chamber, which overcomes the above-noted disadvantages of prior centrifuges of this character.

Another object is to provide a centrifuge of the character described having a simple, compact and rugged construction for introducing the flushing

2

liquid into the separating bowl in such a manner as to prevent any substantial leakage thereof, and which at the same time allows the bowl to be lifted from the frame without interference from the feeding device in its normal position.

A centrifuge made in accordance with the invention comprises a frame having a spindle for rotating the centrifugal bowl. The bowl is provided with an annular recess which is open toward the spindle axis and from which a flushing liquid is adapted to be fed radially outwardly into the separating chamber, the bottom of this recess being formed by an inwardly extending annular ledge on the bowl. The frame is provided with an extension which preferably surrounds the spindle in spaced relation thereto and projects through a space between the annular ledge and the spindle. This extension defines a passage communicating at its inlet end with a duct for feeding a flushing liquid to the passage, and at its outlet end with the inwardly facing recess in the bowl. The frame extension projects axially beyond the outlet end of the liquid passage to form a support for a sleeve assembly which is preferably removable from the support. The sleeve assembly functions to control the discharge of the flushing liquid from the frame passage into the bowl recess. For this purpose, the sleeve assembly may include a part directly overlying the outlet end of the flush liquid passage in the frame extension and forming with the extension a series of discharge passages extending outwardly and generally tangentially in the direction of the bowl rotation. In this way, the flush liquid is broken up into small streams which discharge at fairly high velocity but in the direction of movement of the rotating mass of flush liquid in the bowl recess, whereby splashing, dripping or leaking of the liquid through the clearance space adjacent the bowl ledge is effectively prevented. The mass of liquid within the bowl recess is retained therein by centrifugal force, which also causes the liquid to flow outwardly from the recess into the separating chamber.

In the preferred construction, a further protection against leakage of the flushing liquid is provided by means of a flexible throw-off ring projecting outwardly from the frame extension below the outlet end of the liquid passage therein, the ring overlying the clearance space between the bowl ledge and the frame extension and also overlying the inner part of the ledge. Thus, any flushing liquid tending to drip or spatter through this clearance space will be deflected by the throw-off ring into the rotating mass of liquid.

in the bowl recess. Also, since the throw-off ring is flexible, it allows the bowl to be lifted freely from the frame. Preferably, an annular shield or collar rotating with the bowl extends downwardly around the upper end portion of the frame extension and its sleeve assembly, the collar acting to prevent the passage of flush liquid into the space between the spindle and the frame extension.

For a better understanding of the invention, reference may be had to the accompanying drawing, in which Fig. 1 is a vertical sectional view of part of a preferred form of the separator; and Fig. 2 is a bottom view of part of the flushing assembly illustrated in Fig. 1, showing the tangential discharge passages for the flush liquid.

In the drawing, the numeral 1 designates a centrifugal bowl having an annular separating chamber 2 provided with peripheral outlets 3 in the form of discharge nozzles in the outer wall of the chamber. The mixture to be separated may be fed to the chamber 2 in any desired manner, as through an axial passage in the spindle 4 for rotating the bowl, or through the top (not shown) of the bowl. The heavier solids in the mixture will accumulate at the peripheral portion of chamber 2, due to the action of centrifugal force, and discharge through outlet 3, while the separated lighter constituents of the mixture will be displaced inwardly in chamber 2 and discharge through a separate outlet (not shown).

In order to facilitate discharge of the solid particles through the peripheral outlets 3, the bowl 1 is provided with an annular recess 5 for receiving a flushing liquid, the recess 5 being open toward the spindle 4. The bottom of recess 5 is formed by an inwardly extending annular ledge 5^a on the bowl, whereby a body of the flushing liquid may be retained in recess 5 by the action of centrifugal force during the separating operation. From recess 5, the flushing liquid is delivered through passages 6 and flush tubes 7 in the bowl to the outer part of chamber 2 near or at the entrance to the discharge nozzles 3. It will be understood that the liquid from tubes 7 is adapted to carry or flush the separated solids through the nozzles 3 as the bowl rotates.

The bowl 1 is supported in any suitable manner on the upper end (not shown) of the spindle 4, so that the bowl rotates with the spindle. Intermediate its ends, the spindle is supported laterally by a top bearing 8, the lower part of the shaft being supported by another bearing (not shown). The bearing 8 is seated on a shoulder 4^a on the spindle and is supported in a ring 9 mounted in the frame 10. Preferably, the ring 9 is held in the frame by a rubber cushion, springs, or the like (not shown), so that the ring and therefore the bearing are adapted to move laterally to accommodate vibrations of spindle 4. A disc 11 is clamped against the top of the inner race of bearing 8, as by means of a nut 12 threaded on the spindle, the peripheral part of disc 11 overlying the outer race of the bearing in spaced relation thereto, so as to shield the ball bearings against liquid and other foreign matter which might otherwise drop into the space between the races.

The frame 10 is provided with an annular extension in the form of two complementary annular sections 14 and 15 which surround the spindle and are spaced therefrom, the lower or

horizontal parts of these sections being clamped on the main part 10 of the frame, as by means of bolts 10^a. The sections 14 and 15 have vertically extending parts 14^a and 15^a, respectively, which project upwardly and freely through the annular clearance space between the ledge 5^a and the spindle. A passage 16 formed between the two sections 14 and 15 extends radially inwardly and then upwardly, as shown at 16^a, to a region above the ledge 5^a and opposite the delivery passage 6 for the flushing liquid. The upper part 16^a of the passage is annular, so that it extends completely around the spindle. At its lower and outer part, the passage 16 communicates downwardly through an opening 17 in section 15, with a passage 18, 18^a formed in the main part 10 of the frame. The passage 18^a, in turn, communicates at its inlet end with a duct 19 for supplying the flushing liquid to the centrifuge. Gaskets 20 and 20^a are interposed at the bottom and at the top, respectively, of the lower section 15 and are compressed by tightening the bolts 10^a, so as to prevent leakage of the flushing liquid from the centrifuge frame.

The inner section 15^a of the frame extension projects upwardly beyond the outlet and of passage 16^a, to form a stationary support for a sleeve 22 having a threaded engagement with the section 15^a. A ring 22^a is threaded on the upper part of section 15^a and tightened against the top of sleeve 22 to lock the latter in place. The lower part of sleeve 22 is flanged outwardly, as shown at 22^b, and engages a ring 23 on the upper end of section 14^a. In its lower face, the ring 23 has tangential grooves 23^a leading outwardly from the upper end of passage 16^a and through which the flush liquid passes slightly upwardly into recess 5. Due to the tangential arrangement of the grooves 23^a, the flush liquid is discharged into recess 5 in the general direction of rotation of the recess wall and the mass of liquid in the recess. The resulting tangential discharge of the liquid acts to overcome the tendency for the liquid to splash upon striking the cylindrical wall of the bowl recess or the liquid already in the recess, particularly when large amounts of flush liquid are being supplied to the bowl. It will be understood that similar tangential grooves may be provided in the upper end of section 14^a in place of or in addition to the grooves 23^a.

A sealing ring 22^c, of rubber or the like, is compressed in a groove between sleeve 22 and section 15^a.

Below the ring 23, the outer section 14^a is recessed to receive a flexible annular throw-off ring 25, which may be made of rubber. The ring 25 projects outwardly from section 14^a and overlies the inner part of the annular bowl ledge 5^a. An annular shield 26 is secured to the spindle in the recess 5, as by means of an insert ring 27 and a set screw 26^a, and extends downwardly around the upper part of the sleeve 22, the shield 26 being spaced from the sleeve to permit vertical movement of the latter.

In the operation of the centrifuge, the flushing liquid from passage 16^a is sprayed outwardly through the grooved ring 23 in tangential streams and in the direction of rotation. From recess 5, the liquid is delivered by centrifugal force through tubes 7 to the separating chamber. Preferably, the rate of flow through the supply duct 19 is so regulated that a rotating mass of the liquid accumulates in recess 5 to a vertical level which is maintained well outside the inner

margin of ledge 5^a, so that there is no danger of the liquid overflowing the ledge. However, in the event that any of the liquid should accidentally pass through the annular space 5^b between the ledge and the outer section 14^a, it is prevented from reaching the bearing 8 because of the frame extension 14—15 which, in addition to conducting the flush liquid, forms a protective cap or closure over the bearing. In addition, the liquid is prevented from reaching the bearing from recess 5 through the space between the inner section 15^a and the spindle, because of the shield 26.

The lower throw-off ring 25 serves to catch any liquid tending to drip from the top of the outer section 14^a and to deflect such liquid outwardly upon the ledge 5^a or into the rotating mass of liquid in the recess. Also, the ring 25 is positioned to intercept liquid tending to splatter downwardly through the clearance within ledge 5^a from the rotating mass in recess 5, incident to spraying the liquid from passage 16^a. In this connection, it will be observed that by sloping the grooves 23^a upwardly as shown, the liquid spray is directed upwardly and outwardly so as to practically eliminate any tendency for the liquid to splatter directly downward from the rotating mass through the space 5^b. Thus, the splattered liquid will strike the sleeve 22 (or the sloping edge of its flange 22^b) or the shield 26 and drop upon the deflecting ring 25. Consequently, the new construction is highly effective to prevent leakage of the liquid even upon the protective cap 14—15 for the bearing.

By reason of the tangential distribution of the liquid from the annular passage 16^a, the discharging liquid is combined with and brought into rotation by the mass in recess 5 with a minimum disturbance to this mass, thereby enhancing the ability of the apparatus to provide a smooth, continuous flow of the liquid from the stationary frame to the rotating bowl, without leakage of the liquid incident to the transfer.

It will be apparent that with the new apparatus the bowl 1 may be lifted from the spindle 4 without interference from the means for feeding the flush liquid, since the deflecting ring 25 can flex upwardly to allow the bowl ledge 5^a to pass over it, and there is ample clearance between the ledge and both the outer section 14^a of the frame extension and the shield 26. Moreover, the stationary parts 14 and 15 for delivering the flush liquid are compact and rugged and do not interfere in any way with the operation of the bowl or the feed and discharge of the material to be separated. The ring 25 can be expanded, due to its elasticity, to permit it to be easily mounted on or removed from the assembly. The extension 14—15 is removable from the frame to facilitate access to bearing 8.

It will be understood that the distributor ring 23 may be replaced by a ring having different distributing characteristics. Also, it may be omitted by forming the distributing grooves in sleeve 22 or in the upper end of section 14^a engaged by the sleeve, or in both.

I claim:

1. In a centrifuge having a frame, a spindle in the frame, and a bowl rotatable on the spindle and defining a separating chamber, the bowl having an annular recess opening toward the spindle axis and adapted to receive a flushing liquid to be conveyed radially outward to the separating chamber, and the bowl having an inwardly extending annular ledge forming the bot-

tom of the recess, the combination of a pair of complementary annular stationary sections mounted on the frame concentric with the spindle and defining an annular passage surrounding the spindle and communicating at its outlet end with the recess, said outlet end of the passage being located above the level of the bowl ledge and between the spindle axis and said recess, a duct communicating with the inlet end of said passage for supplying a flushing liquid thereto, and a stationary ring mounted on one of said members at said outlet end of the passage and coacting with the other member to distribute the liquid from the passage into said recess.

2. A combination as defined in claim 1, in which said ring has tangential grooves connecting said passage to the recess.

3. A combination as defined in claim 1, in which each of said sections has a stationary flat radial portion secured to the frame and also has a sleeve portion projecting from the flat portion into the space between said ledge and the spindle axis.

4. In a centrifuge having a frame, a spindle in the frame, a bowl rotatable on the spindle and defining a separating chamber and also defining an annular recess communicating radially outward with the chamber and opening toward the spindle axis, and a bearing for the spindle mounted in the frame below the bowl, the combination of a stationary protective cap on the frame covering the bearing and projecting upwardly into a space located radially inwardly from said recess, the cap surrounding the spindle and being removable from the frame to permit access to the bearing, the cap defining an annular passage surrounding the spindle and communicating at its upper end with said recess, and a stationary duct connected to the cap for supplying a flushing liquid to said passage.

5. A combination as defined in claim 4, comprising also a ring mounted on the cap at the outlet end of said passage for directing flushing liquid outwardly from the cap passage into said recess.

6. A combination as defined in claim 1, in which said other member and the ring have generally radial, inter-engageable surfaces at the outlet end of said last passage, whereby the flushing liquid is directed radially outward from the passage into said recess.

7. A combination as defined in claim 1, comprising also a flexible throw-off ring projecting radially outward from said other member into the recess below the distributing ring and overlying the inner portion of the bowl ledge.

8. A combination as defined in claim 1, comprising also a bearing for the spindle below the bowl, said members forming a cap overlying the bearing.

9. A combination as defined in claim 1, comprising also a shield in the recess rotatable with the bowl and surrounding part of said members with a clearance between the shield and said members.

10. A combination as defined in claim 1, comprising also a shield in the recess mounted on the spindle and surrounding part of said members with a clearance between the shield and said members.

11. In a centrifuge having a frame, a spindle in the frame, and a bowl rotatable on the spindle and defining a separating chamber, the bowl having an annular recess opening toward the spindle axis and adapted to receive a flushing liquid to be

conveyed radially outward to the separating chamber, the bowl having an inwardly extending annular ledge forming the bottom of the recess and spaced from the spindle, the combination of a hollow annular extension on the frame surrounding the spindle and projecting upwardly therefrom through the space between the spindle and the bowl ledge in spaced relation to said spindle and ledge, the extension defining an annular passage communicating at its outlet end with the recess above the level of the ledge, the extension having a cylindrical part surrounding the spindle and projecting upwardly beyond the outlet end of said passage, a duct communicating with the inlet end of the passage for supplying a flushing liquid thereto, a ring mounted on said cylindrical part and operable to direct the flushing liquid tangentially outwardly from said passage into the recess, and a flexible throw-off ring projecting outwardly from said extension into the recess below the cylindrical part and overlying the inner portion of said ledge.

12. A combination as defined in claim 11, comprising also an annular shield rotatable with the bowl and extending downwardly around the upper portion of said cylindrical part in spaced relation thereto.

13. The combination as defined in claim 11, comprising also a bearing for the spindle located below the bowl, said extension forming a removable cap overlying the bearing.

14. In a centrifuge having a frame, and a bowl rotatable in the frame and defining a separating chamber, the bowl having an annular recess open-

ing toward the rotational axis of the bowl and adapted to receive a flushing liquid to be conveyed radially outward to the separating chamber, the combination of an annular extension on the frame surrounding the spindle and projecting between said recess and the bowl axis the extension being hollow and defining an annular passage having inlet and outlet ends, said outlet end communicating radially outwardly with said recess, a duct communicating with the inlet end of the passage for supplying a flushing liquid thereto, and a ring coaxing with said extension to confine the discharge of liquid from the annular passage, said ring and extension having opposed surfaces extending outwardly from the passage, at least one of said surfaces having grooves extending generally tangentially in the direction of rotation of the bowl.
